UNITED STATES PATENT OFFICE.

HAROLD G. BAXTER, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCH MECHANISM.

Application filed April 18, 1922. Serial No. 555,128.

My invention relates to enclosed switch mechanisms and particularly to enclosed switch mechanisms of the safety type that are adapted for use in mines.

5 One object of my invention is to provide an enclosed switch mechanism wherein the housing is of sufficient strength to withstand explosions of gas within the casing and of such construction that the gases escaping 10 from the casing are cooled and extinguished before they reach the atmosphere.

Another object of my invention is to provide a switch mechanism, having the above 15 characteristics, wherein the switch and door are so interlocked that the latter cannot be opened so long as the switch is in closed position or the switch closed so long as the door is in open position.

Another object of my invention is to provide 20 an enclosed switch mechanism wherein the casing is made entirely of cast metal and wherein the door is provided, along its hinged edge, with means interfitting with the edge of a stationary portion of the cover 25 for inhibiting the gas in its passage through the joint and constituting a tortuous path to insure thorough cooling of the gases before reaching the atmosphere.

Another object of my invention is to provide 30 an enclosed switch of heavy and rugged construction adapted for use in mines and on mine locomotives and wherein the hinged door is provided with a lock that engages the housing at a plurality of remote points for 35 securely retaining the door in closed position against the action of explosive forces within the housing.

A further object of my invention is to provide 40 a latch for the door having an interlock co-operating with the switch for preventing releasing movement of the lock so long as the switch is in closed position.

These and other objects, that will be made 45 apparent throughout the further description of my invention, may be attained by means of the switch mechanism hereinafter described, and illustrated in the accompanying drawings, wherein:

Figure 1 is a front view of the switch 50 mechanism showing a portion of the stationary cover removed;

Fig. 2 is a longitudinal section through the switch housing, taken on the broken line II—II of Fig. 1;

Fig. 3 is a transverse section through the 55 housing, taken on the line III—III of Fig. 2;

Figs. 4 and 5 are front and side views, 60 respectively, of the door-locking plate.

Fig. 6 is a longitudinal section in enlarged 65 scale of the switch mechanism showing the switch-operating elements in side elevation, and

Fig. 7 is a side elevational view of the 70 switch mechanism showing the exteriorly disposed interlocking cams.

Referring to the drawings, the apparatus includes a metal housing 6 upon which is secured a metal cover portion 7 that is attached to the housing by means of bolts 8. 75 The housing is provided with a movable door 9 having hinge brackets 10 thereon that co-operate with brackets 11 on the cover portion 7. A hinge bolt 12 extends through the brackets.

A switch panel 13 is mounted within the 80 housing and supports a switch mechanism 14 and fuse clips 15 that are adapted to receive knife-blade cartridge fuses (not shown).

The switch 14 may be of any preferred construction and is of the oscillatory type. The switch comprises laminated brushes 16 that are pivoted upon a shaft 17 supported on brackets 18 that are mounted on the base 85 13. The switch is operated by means of an operating rod 19 that is pivoted to the side walls of the housing and which extends exteriorly thereof. An operating handle 21 is attached to the projecting end of the 90 operating rod.

The operating rod 19 is connected to the switch brushes through the medium of a bracket 22 that is pivoted upon the shaft 23 secured to the support 18. The bracket is provided with a crank arm 24 having a pin 25 that engages a slot 26 in a lever 27 that is pivotally mounted upon the shaft 23 and provides a lost-motion connection between the operating rod 19 and the knee pivot 20 of the toggle. The shaft 23 is provided with a toggle arm 28 to which the switch 100

brushes 16 are connected by means of a toggle link 29.

A spring 31 normally tends to yieldingly retain the switch in open position and, when the switch is moved to the closed position indicated in Fig. 2, the toggle links 28 and 29 serve to retain the switch brushes in engagement with the contact terminals 32 and 33, the toggle links, at such time, being in the "made" position indicated in Fig. 2.

When the operating rod 19 is turned counterclockwise, the left shoulder 30 of the floating lever 27 engages the knee pivot of the toggle and causes it to collapse. Engagement, however, does not take place until after the operating handle has been moved a predetermined distance toward open position. The switch is closed by engagement of the right end of the floating lever 27 with the knee pivot of the toggle links after the handle has been moved a predetermined distance toward closed position.

The switch construction above described is well known in the art and it is believed unnecessary to go into further details as to its construction. It is obvious that, when the toggle link is broken, the switch is moved to open position with a snap action.

The circuit through the switch and fuses is such that, when the switch is open, the fuse clips and fuses are disconnected from the current source.

The switch herein illustrated is particularly adapted for use on electric locomotives operating in mines where it is very desirable to eliminate any possibility of sparks from the switches igniting the gases usually prevalent in mines. It is, therefore, desirable to enclose all switch mechanisms in casings of such construction that flames incident to explosions of gases leaking into boxes are extinguished before the gases escape therefrom.

The operating rod 19 of the switch is biased toward either open or closed position by means of a helical spring 40 that moves past "dead center" when moved from one position to another. This spring causes the switch to be closed with a snap action in opposition to the spring 31 which normally tends to hold the switch in open position.

The switch mechanism above described is for controlling the main circuits of the locomotive, and the housing is provided with an auxiliary rotary snap switch 34, of any preferred type, for controlling the current supplied to the headlight of the locomotive. Auxiliary fuse clips 35 are provided at the point between the clips 15 for the fuses connected with the headlight circuit. The switch 34 is connected to an operating handle 36 by means of a shaft 37 that extends through a gas-tight bearing 38.

It is very desirable, in a switch of this

character, to prevent any possibility of moving the switch to open position while the cover is in open position in order to preclude the formation of an arc while the switch is exposed to the atmosphere.

The operating rod 19 is provided with a cam member 39 having an arcuate edge 41 concentric with the axis of rotation of the operating rod 19. The cam is also provided with an arcuate edge 42 that is adapted to be moved into a position wherein it is concentric with the axis of rotation of the door 9 when the switch is in open position.

The door 9 is provided with a cam member 43 having a convex edge concentric to the axis of rotation of the door 9 and a concave edge 44 that is concentric to the axis of rotation of the shaft 23 when the door is in closed position. By reason of the arrangement of the cam members 39 and 43, which are disposed in the same plane exteriorly of the housing, opening movement of the door is prevented so long as the switch is in the closed position indicated in Fig. 2. By reason of the engagement of the concave surface 44 with the arcuate edge 41 of the cam member 39, opening movement of the cover 9 is precluded until after the switch has moved into extreme open position wherein the cam member 39 clears the cam 43 and permits opening movement of the door.

When the door is moved slightly out of closed position, the corner 45 of the cam member 43 is moved across the path of movement of the cam member 39 and prevents closing movement of the switch. The switch cannot be closed, therefore, so long as the door is in any other than fully closed position.

As the pressure, generated in the housing by an explosion of mine gases therein, is extremely high, it is necessary to provide ample means for securing the door in closed position so that the door provides a tight seal which permits the gases to escape gradually and which cools them sufficiently to extinguish them before they reach the atmosphere. I have, therefore, provided a rotatable lock plate 46, Fig. 5, mounted upon a shaft 47 that projects exteriorly of the door and is provided with an operating handle 48. The plate is provided with three arcuate slots 49 adjacent the peripheral edge thereof through which extend stationary rivets 51 that are secured to the inner side of the door.

The rivets are provided with enlarged heads 52 that serve to support the plate against longitudinal displacement. The plate is provided with latch extensions 53 that project beneath lugs 54 that are bolted in slots provided in the edge flange of the housing. When the plate 46 is in the locked position indicated in Fig. 1, the extensions

53 engage the inner surfaces of the lugs 54 which are inclined slightly and serve to cam the door tightly in closed position.

The plate 46 is provided with a notch 55 that is adapted to receive the end 56 of a latch rod 57 that is slidably mounted upon the underside of the door and secured thereto by means of clips 58. The end of the bar adjacent the switch is provided with an inwardly-turned end 59 that is adapted to be engaged by the operating rod 19 and moved thereby when the rod is moved to closed position. Movement of the rod to the right causes the end 56 to engage the slot 55 in the plate 46 and prevent rotary movement of the plate so long as the switch is in closed position.

A helical spring 61 surrounds the rod 57 and is disposed between one of the clips 58 and a collar 62 secured to the bar. This spring normally tends to move the latch bar 57 out of engagement with the slot 55 when the switch is moved to open position.

It is apparent, therefore, that the latch plate 46 can not be moved to release the cover so long as the switch is in closed position. Therefore, there is no danger of gaining access to the interior of the housing except when the switch is in open position.

In order to insure that the joint between the stationary portion of the cover 7 and the door 9 is substantially gas tight, the free edge of the cover 7 is provided with a tongue 63 that snugly fits the groove 64. This construction provides a tortuous passage for the escaping gases.

It is understood that no attempt is made to absolutely prevent the escape of gases from the housing, it being the purpose only to prevent the ignited gases from escaping from the housing before they are extinguished.

While I have described and illustrated but one embodiment of my invention, it will be apparent to those skilled in the art that various changes, modifications, substitutions, additions and omissions may be made therein

without departing from the spirit and scope of my invention as set forth in the appended claims.

50

I claim as my invention:

1. Switch mechanism comprising a housing, a switch within the housing, a door hinged at one edge to the housing, a rotatable locking plate on the door slidably supported at a plurality of points respectively adjacent to the other edges of said door and having portions adjacent to each of the points of support for engaging the housing whereby all of the edges of the door may be secured in closed position and means for interlocking the said plate with the switch whereby opening movement of the plate is prevented so long as the switch is in closed position.

65

2. Switch mechanism comprising a housing, a movable switch within the housing, a door hinged at one edge to the housing, a locking member rotatably mounted on the door and secured thereto at points adjacent to the other edges and engaging the housing adjacent to each of said points for retaining the door in closed position, and an interlock rod slidably mounted on the door and actuated by the switch for engaging the locking member and for preventing opening movement thereof so long as the switch is in other than fully open position.

70

3. Switch mechanism comprising a housing, a movable switch within the housing, a door hinged at one edge to the housing, a locking member rotatably mounted on the door for engaging the housing and retaining the door in closed position, the said member being provided with a radial slot, and an interlocking rod slidably mounted upon the cover and movable by the switch into the slot when the switch is moved to closed position for preventing releasing movement of the locking member.

80

In testimony whereof, I have hereunto subscribed my name this 17th day of April, 1922.

HAROLD G. BAXTER.
